UNITED STATES PATENT OFFICE.

HENRY BRUCK, OF PORTLAND, OREGON.

REINFORCEMENT FOR THE SHANK EDGES OF SHOE-TAPS.

1,341,880.

Specification of Letters Patent. Patented June 1, 1920.

Application filed November 3, 1919. Serial No. 335,271.

To all whom it may concern:

Be it known that I, HENRY BRUCK, a citizen of the United States, residing at Portland, in the county of Multnomah and 5 State of Oregon, have invented a new and useful Improvement in Reinforcements for the Shank Edges of Shoe-Taps, of which the following is a specification.

This invention relates to composition shoe 10 soles and has particular reference to an improvement in half soles or so-called taps.

In the making of whole soles of rubber or rubber composition, little or no difficulty presents itself in attaching the soles to the 15 welt of the shoe. However, such is not the case in connection with half soles for the reason that while the side edges of the sole may be sewed or stitched to the welt the rear or shank edge thereof must be nailed down, 20 and by reason of the strains imposed on the sole at this point it was found necessary to reinforce the shank edge thereof in a practical manner which would meet all of the requirements of application and use. The 25 patent to Shoemaker and Bruck, No. 1,239,628, dated September 11, 1917, shows a thoroughly practical and successful means for reinforcing the half sole at the shank edge, and the present invention aims to attain 30 the same end in a somewhat different manner while at the same time maintaining all of the advantages of the type of reinforcement shown in said patent.

The patent to Shoemaker and Bruck referred to, wherein I am a joint inventor, 35 illustrates and describes a half sole made of a rubber composition having its shank edge reinforced by a strip of folded fabric placed astride an intermediate layer of the 40 sole whereby during the vulcanizing step, in the manufacture of the sole, the engagement of the folded fabric over the intermediate layer will serve to hold the same in place and prevent it from being shifted up 45 into the body of the sole under pressure of the mold in producing the skived or beveled edge at the rear end of the tap. The spaced plies produced by the folded fabric therefore provide a thoroughly practical and efficient 50 and well distributed reinforcement for the shank edge of the shoe tap, while the folded edge serves as an anchor for the material during the manufacturing process. Nevertheless, it has been found desirable to meet 55 certain manufacturing requirements and also make a cheaper product to utilize a

single ply of fabric, but heretofore on account of a single piece of fabric offering no resistance against slipping under the pressure of the molding operation, and also because of the fact that it was necessary to utilize a heavier fabric which in use caused the sole to crack where the bulk of the composition and fabric joined, it could not be successfully used. However, by reason 60 of improved manufacturing methods and equipment the tendency of the reinforcement to slip under the molding pressure has been eliminated through the use of special anchoring means in the mold, while at the same 65 time the use of a relatively heavy fabric without the objectionable results referred to is made possible by the novel character of the fabric reinforcement proposed by the present invention. 70

Accordingly, a primary object of the invention is to provide a fabric reinforcement for the shank edge of a half sole which may be used in the form of a single ply of sufficient thickness and toughness to withstand 75 the pulling stress imposed thereon by the holding nails at the shank edge of the tap while at the same time being so designed and arranged as to prevent the cracking of the composition along the line where the reinforcement stops toward the front portion of the tap. 80

A further object incidental to the foregoing primary object is to provide a fabric reinforcing unit which obviates the necessity of using a multiplicity of thickness to obtain the required reinforcement. 90

With the above and other objects in view which will more readily appear as the nature of the invention is better understood 95 the same consists in the novel construction, combination and arrangement of parts hereinafter more fully described, illustrated and claimed.

A preferred and practical embodiment of 100 the invention is shown in the accompanying drawings, in which:—

Figure 1 is a plan view of a shoe tap showing the reinforcement therein in dotted lines. 105

Fig. 2 is a detail perspective view of the reinforcing strip.

Fig. 3 is an enlarged horizontal section taken on the line 3—3 of Fig. 1.

Similar reference characters designate 110 corresponding parts throughout the several figures of the drawings.

According to the patent, previously referred to, it is proposed to utilize a folded reinforcing material consisting of spaced plies embedded in the composition at the rear or shank edge of the tap, the said spaced plies preferably straddling an intermediate layer or portion of composition which constitutes the body of the sole. This is a very advantageous arrangement since it not only provides a reinforcement sufficiently strong and well distributed to withstand the strains imposed thereupon, but at the same time provides for holding the reinforcement in place at the rear edge of the tap during manufacture. Furthermore, the employment of spaced plies provided for the distribution of the reinforcement in such a manner that the sole would not break or crack where the reinforcement terminated at its inner edge. Accordingly, the present invention aims to preserve these features and advantages by the use of an unfolded unit of fabric, that is a fabric reinforcement which may be either in the form of a single ply, or a plurality of thicknesses arranged layer to layer to provide a single unit of reinforcement as distinguished from a plurality of thicknesses having a portion of the sole material arranged therebetween. In other words, it is to be understood that it is within the scope of the present invention to utilize more than one thickness to constitute a single ply of reinforcing material to obtain the desired thickness to properly reinforce the shank edge of the tap.

The improved manufacturing methods by which a single ply or unit of reinforcing material may be utilized may involve many different forms and types of apparatus, but one way which has been found to be successful, is the provision of a series of anchoring pins or their equivalent in the mold which engage the reinforcing strip and serve to securely hold it in position when the plastic sole composition is subjected to pressure in the molding operation. Through the utilization of special equipment the tendency of the single fabric unit to slip during the process of manufacture has therefore been corrected, and in order to provide for such an embedment and union the relatively heavy unit of reinforcing fabric and the sole composition it is proposed to provide a reinforcing strip having the novel characteristics to be now referred to.

That is to say it is proposed to provide a fabric reinforcement strip 1 which meets all of the requirements as to thickness and weight according to the size and character of the sole in which it is to be embedded, and which is provided with an irregular edge 2 that may be of serrated or incised formation and adapted to be placed in the sole with the said serrated or incised edge disposed toward the toe thereof while the

plain rear edge 3 is located at the rear edge of the tap. By reason of the serrated, toothed, or equivalent formation of the inner edge of the reinforcement there is provided a plurality of forwardly projecting tongues 4 which serve to distribute the front edge of the reinforcement in such a manner that a sharp line of departure between the same and the rubber composition is entirely obviated or avoided. In other words the invention has as one of its novel and distinctive features the provision of a unit of reinforcement for the shank edge of a composition half sole which has its inner edge broken up in any suitable manner that will prevent an abrupt joint where it projects into the body of the sole to thus prevent cracking of the sole at the part which is subjected to the greatest bending and pulling stresses.

The formation of the serrated or like edge on the reinforcing material has the special advantage of permitting the use of comparatively heavy fabrics for the reinforcement strip, and it will of course be understood that the invention is not limited to the particular shape, length or disposition of the anchoring tongues 3 which provide in effect a graduated embedment for the fabric at its front edge.

Without further description it is thought that the features of the invention will be readily apparent to those skilled in the art, and it will of course be understood that changes in form and proportion may be resorted to without departing from the features defined by the appended claims.

I claim:

1. A reinforced shoe tap including the tap body and a reinforcing strip embedded in the shank edge thereof, said strip having one edge formed with a plurality of projections.

2. A reinforced shoe tap including the tap body and a reinforcing strip embedded in the shank edge thereof, said strip having at the front edge thereof a plurality of spaced projecting tongues disposed toward the toe of the tap body.

3. A reinforced shoe tap including the tap body and a reinforcing strip embedded in the shank edge thereof, said strip having a plain rear edge and a serrated front edge.

4. A reinforced shoe tap including the tap body and a unit of fabric of relatively great thickness having an irregular inside edge portion to provide a graduated joint between the front edge of the fabric and the body of the tap.

5. A reinforced shoe tap including the tap body having at the shank edge a single strip of unfolded fabric provided with a plurality of embedment tongues projecting from the front edge thereof and into the body of the tap, said strip being embodied within the

shank edge of the tap and extending transversely thereof in the nail receiving zone.

5. A reinforced shoe tap including the tap body and a reinforcing strip embedded in the shank edge thereof, said strip having a broken edge portion interlocking with the body.

7. A reinforced shoe tap including the tap body and a reinforcing strip embedded in

the shank edge of said body and having a 10 sinuous edge portion interlocking therewith.

In testimony that I claim the foregoing as my own I have hereto affixed my signature in the presence of two witnesses.

HENRY BRUCK.
